UNITED STATES PATENT OFFICE

2,083,474

HIGH FREQUENCY RECEIVING APPARATUS

Ernest Yeoman Robinson, Enfield, England, assignor to General Electric Company, a corporation of New York

Application July 25, 1934, Serial No. 736,837
In Great Britain November 8, 1933

5 Claims. (Cl. 250—20)

My invention relates to high frequency receiving apparatus and more particularly to such apparatus incorporating automatic volume control means.

In high frequency receivers provided with automatic volume control means the gain of the receiver is varied inversely with the incoming signal and therefore the gain of the receiver is greater when the receiver is off tune with the incoming carrier wave. For example, if the receiver be tuned to an incoming modulated carrier wave and the tuning of the receiver be varied, the sensitivity of the receiver first increases as the receiver is gradually detuned from the condition of resonance with the received carrier wave, and continues to increase until the incoming signal after amplification is of such a low amplitude that the voltage after amplification does not exceed the delay voltage on the automatic volume control circuit. Subsequently the sensitivity of the receiver remains constant unless it is arranged for noise suppression, in which case at some state after the receiver has reached maximum sensitivity the output voltage from the receiver is reduced to zero.

When the receiver is not properly in tune with the carrier wave but is sufficiently in tune therewith to remove the noise suppression voltage applied, for example, to the low frequency amplifier of the receiver, the sensitivity of the receiver is greatly above normal, thus leading to excessive amplification of the side bands due to the higher audio frequencies. This effect renders the operation of the receiver very unpleasant particularly when stations of a strong field strength are being received.

Further owing to the fact that the amplification of the receiver is increased as the receiver is detuned from resonance with the received carrier wave the aural output volume of such a receiver may be held constant, or even increased, over a certain range of the tuning control on either side of resonance. Aural tuning of the receiver is, therefore, rendered difficult and additional devices such as visual tuning meters are desirable.

One object of the present invention is to provide a new method of noise suppression, whereby the receiver has a very low inter-channel gain. A second object of the invention is to provide means whereby excessive amplification of the receiver when it is tuned to the side band of the received signal is reduced, whereby the generation of unpleasant noises and side band shriek is eliminated or reduced. A third object of the

invention is to provide means whereby the acoustic output of the receiver is greatest when the receiver is exactly in tune with the incoming signal, whereby the receiver may be accurately tuned by aural means and without recourse to additional devices such as visual tuning meters.

The novel features which I believe to be characteristic of my invention are set forth with particularity in the appended claims. My invention itself, however, both as to its organization and method of operation together with further objects and advantages thereof may best be understood by reference to the following description taken in connection with the accompanying drawings in which Figs. 1, 3, and 4 to 7 represent different embodiments of my invention, and Fig. 2 represents certain characteristics of the operation of the form of the invention shown in Fig. 1.

Referring to Fig. 1 of the drawings I have shown therein a portion of the circuits of a radio receiver involving electron discharge devices 1, 2 and 3. The electron discharge device 1 is a radio frequency amplifier of the conventional variable mu type, this tube being provided with the well known variable pitch control grid 4, 25 a screen 5, and suppressor grid 6, the latter being connected directly to the cathode 1. The control grid 4 is connected to a tuned input circuit 8 to which radio frequency electromotive forces may be supplied either from the antenna circuit, 30 or from preceding stages, not shown, of the receiver. The anode of the discharge device 1 is likewise connected to a tuned output circuit 9 which in turn is closely coupled to a tuned circuit 10 comprising the input circuit of the electron discharge device 2.

The discharge device 2, as shown, is one of the type having a cathode 11 which cooperates with an anode 12 in the manner of the electrodes of a diode. It also cooperates with a variable 40 pitch control grid 4', screen grid 13, suppressor grid 14 and anode 15 in the same manner as in discharge device 1. The anode 15 of the discharge device 2 is connected to a tuned circuit 16, 45 which is loosely coupled to a tuned circuit 18, these circuits being loosely coupled for high selectivity, the circuit 18 comprising the input circuit to the valve 3.

The electron discharge device 3 is provided with a cathode and two anodes 19 between the latter of which the tuned circuit 18 is connected, this portion of the discharge device 3 cooperating in the manner of a full wave detector or rectifier. The discharge device 3 is also provided with five 55

grids G_1 , G_2 , G_3 , G_4 , G_5 and an anode 20 which cooperate in a manner later to be described.

It will now be observed that high frequency oscillations supplied to the input circuit 8 are amplified in discharge device 1 and supplied through circuits 9 and 10 to the diode rectifier of the discharge device 2 , and also to grid $4'$ of device 2 in which they are amplified and supplied to circuit 17 . Rectifier 11 , 12 is the automatic volume control rectifier of the radio receiver, the anode being connected to the cathode through a load resistance 21 and a cathode bias resistor 22 , this latter resistor being connected between the cathode of the discharge device and the negative side of the power supply to the different discharge devices. This power supply is indicated by the conductors marked plus and minus and supplies energy to the different electrodes of all of the discharge devices. It is bypassed for radio frequency currents by condenser C . The current flowing between the cathode and anode 15 of discharge device 2 is sufficiently great to prevent any flow of current in the diode 11 , 12 and in resistance 21 when the received carrier wave has an intensity less than a certain predetermined value. When the received high frequency electromotive force is greater than said predetermined intensity a unidirectional voltage appears upon resistance 21 causing the upper terminal thereof to become negative, this negative unidirectional voltage being applied through the filter comprising resistance 23 and condenser $23'$, and input circuit 8 , to the grid of discharge device 1 , and through input circuit 10 to grid $4'$ of discharge device 2 . In this way the grids of discharge devices 1 and 2 are driven negatively by an amount sufficient to maintain the signal wave electromotive forces in the circuit 17 substantially constant irrespective of any variations in intensity of the received carrier wave produced, for example, as by fading.

High frequency oscillations in the circuit 17 are supplied to the rectifier section 18 , 19 of the discharge device 3 whereby they are rectified. When this occurs a unidirectional voltage, and also the audio frequency voltage resulting from demodulation of the carrier wave, are produced upon resistance 24 which is connected between the cathode and an intermediate point on the inductance of the tuned circuit 18 . The unidirectional voltage produced on this resistance is supplied to the control grid G_1 of device 3 through a resistance 25 . The audio frequency voltage is likewise applied to this grid through a condenser 26 which may be variably connected to the resistance 24 for manual volume control purposes. Grid G_1 is a variable pitch grid similar to grids 4 and $4'$ of devices 1 and 2 .

The action of discharge device 3 will now be described. It will be observed that the anode 20 of the discharge device 3 is connected to the positive side of the power source through a resistance 27 and that grids G_2 and G_4 are connected directly to the positive side of this supply source. The cathode is connected to the negative side of the supply source through a resistance 28 , and the grid G_3 is connected through a resistance 29 to an intermediate point on a bleeder resistance 30 across the supply source.

In the absence of a signal in the circuit 18 having intensity greater than a predetermined amplitude, due to current flowing in resistance 28 and the tap connection of resistance 29 to resistance 30 , the grid G_3 is sufficiently negative with respect to the cathode to preclude the flow of any

current to anode 20 . All of the current flowing through resistance 28 flows from the grid G_2 to the cathode. This prevents any audio frequency output from appearing on resistance 27 where it might be tapped off through an output condenser 31 to any desired load circuit such as a loudspeaker or subsequent audio amplifier. This predetermined intensity may be so chosen as to preclude the production of noise currents in the output when the carrier is of less than a desired value.

As the signal electromotive force in circuits 17 and 18 increases, however, the unidirectional voltage on resistance 24 increases thereby driving the grid G_1 increasingly negative with respect to the cathode. This in turn reduces the amount of current flowing in resistance 28 and thereby causes the grid G_3 to become gradually less negative with respect to the cathode. When the received signal exceeds the said predetermined amplitude current starts to flow in the resistance 27 across which the audio voltage appears which is supplied through the condenser 31 to the load circuit. This output thus increases in accordance with the intensity of the received signal wave due to the increased amplification of the amplifier section of the valve 3 in response to the increased carrier wave.

In this way noise suppression in the receiver is effected. Electromotive forces supplied to the grid G_1 , due to atmospheric electricity, static, etc. are not ordinarily of sufficient mean value to affect appreciably the voltage on grid G_3 . By means of resistance 29 and bypass condenser $29'$, the circuit of grid G_3 is given a time constant such that large atmospheric and static electromotive forces do not appreciably affect this grid. In this way and by proper adjustment of the tap point of resistance 29 to resistance 30 atmospherics and other interference may be completely suppressed.

The tuning elements of the tuned circuits 8 , 9 , 10 , 17 and 18 may if desired be provided with unicontrol means whereby the receiver may be tuned to any desired frequency. Preferably, however, these circuits are comprised in the intermediate frequency portion of a superheterodyne receiver whereby they may be tuned to a single fixed frequency. In such a receiver the intermediate frequency is supplied to the circuit 8 from the first detector, not shown, which may be tuned by unicontrol with the tuning of a local oscillator and antenna circuit, which may include radio amplifiers. These portions of the equipment being entirely conventional are omitted for simplicity of the drawings. Thus when the receiver is in tune with any desired carrier wave a constant intermediate frequency is supplied to the circuit 8 . Upon variation of the unicontrol member in either direction from the resonance position, however, the intermediate frequency varies and is, therefore, rapidly attenuated by reason of the selectivity of the radio, and intermediate frequency, circuits.

The operation of my invention with respect to aural tuning may now be described. Let us assume that tuned circuits 8 , 9 , 10 , 17 and 18 are all adjusted for resonance with a desired intermediate frequency, which varies in amplitude, as due to fading. Due to the automatic volume control action of diodes 11 and 12 the amplification of amplifiers 1 and 2 , and if desired, earlier radio frequency stages, is varied inversely with the intensity of the received carrier wave with the result that a substantially constant carrier electro-

motive force is maintained in circuits 17 and 18. This result may be obtained to an extremely high degree particularly in view of the fact that the automatic volume control results from rectification of the high frequency voltage at a point in the circuit prior to the amplification produced by the amplifier section of discharge device 2. The amplification of discharge device 3, therefore, remains constant irrespective of the intensity of received signals, and the output audio volume likewise remains constant.

Let us assume now that the input voltage applied to the receiver is constant but that the intermediate frequency varies by reason of variation of the tuning of the local oscillator from the point where the exact desired intermediate frequency is produced. As this variation in frequency occurs the signal intensity applied to the rectifier 11, 12, of course, reduces by reason of the selectivity of the circuits thereby causing increased amplification of the discharge devices 1 and 2 and a tendency to cause either a constant or an increased carrier voltage in the circuit 17 over a certain range of operation of the tuning control. However, owing to the greater selectivity of the circuits between the input to the receiver and the anodes 19, over that between the input to the receiver and the anode 12 a reduction in the signal voltage appearing in circuit 18 immediately occurs, this reduction in carrier wave voltage greatly reducing the amplification of the discharge device 3 until a point is reached where no output occurs. It will thus be seen that in the tuning operation a relatively sharp maximum in the audio output of the receiver is produced when the receiver is exactly in tune with the received carrier wave. This characteristic of the apparatus greatly facilitates the tuning of the radio receiver by the aid of the aural response notwithstanding the use of the automatic volume control circuits.

This latter characteristic of the apparatus also has the desired advantage that it reduces the unpleasant sounds produced in the radio receiver commonly known as side band shriek. These sounds are produced when the radio receiver is adjusted for resonance with a side band of a received carrier wave owing to the increased amplification of the amplifiers as the receiver is detuned for resonance with the carrier wave. Since in accordance with my invention the amplification of the discharge device 3 is reduced at this time these side band shrieks are removed.

To increase the effectiveness of the operation of my apparatus both for aural tuning purposes and for reduction of side band shriek, and intermediate channel gain, it is desirable that the selectivity of the portion of radio receiver prior to the anodes 19 be as much greater than that of the portion 55 of the receiver prior to anode 12 as possible. For this reason circuits 9 and 10 desirably are relatively closely coupled whereas circuits 17 and 18 are relatively loosely coupled. Of course this difference in selectivity may be increased by any of the well known expedients, such as the inclusion 60 of additional stages of amplification or tuning between the circuits 17 and 19.

In Fig. 2 I have shown certain characteristics of the operation of the discharge device 3 of Fig. 1. The curves a, b, c, d, and e of this figure express 70 the relation between voltage E_{G_1} applied to the control grid plotted as abscissa and current I_a flowing in the anode of the discharge device for different values of voltages E_{G_3} between the cathode 75 and the grid G_3 . The curve a expresses the

relation between the current in the anode and the control grid voltage when the voltage between the grid G_3 and the cathode is relatively large, whereas the curve e expresses the same relation when the voltage between the cathode and the 5 voltage G_3 is relatively small, curves b, c, and d expressing the same relation for intermediate values of the voltage between the cathode and the grid G_3 .

In the circuit illustrated the variation of the 10 unidirectional voltage applied to control grid G_1 causes a variation in the unidirectional voltage E_{G_1} appearing between the cathode and the grid G_3 . The dotted line f represents the locus of the 15 latter voltage occurring as the control grid voltage increases. That is, the curve f is drawn through points on the curves a to e, each of which points corresponds to the value of I_a which may occur when the voltage E_{G_1} is such as 20 to produce a voltage E_{G_3} corresponding to the different curves. Of course the pitch of this curve may be varied by variation of the different resistances and connections affecting the potentials on grids E_{G_1} and E_{G_3} .

Fig. 3 shows a different embodiment of the invention in which the noise suppression feature of the apparatus shown in Fig. 1 is not employed. In this figure high frequency oscillations from the output 9 of amplifier 1 are supplied directly 30 through condenser 33 to an automatic volume control diode 12', 11'. This diode although represented as in a separate envelope from the discharge device 2 has its cathode connected with the cathode of the discharge device 2 and functions in the same way as the diode 11, 12 of Fig. 1. The bias resistance 22 in the cathode circuit of discharge device 2 serves to produce a delay bias between the anode and cathode of the automatic volume control rectifier as previously described. The voltage on the load resistance 21 of the automatic volume control rectifier is supplied through the filter comprising resistance 23 and condenser 23' to the grid of the radio frequency amplifier 1 and also through resistances 34 and 35 to the grid of amplifier 2, which amplifier in this case serves as an audio amplifier, the output of which is coupled thereto through a condenser 36. Resistance 34 is the load resistance of the aural tuning rectifier 37 of the apparatus, 50 this rectifier being connected across a tuned circuit 38 which is loosely coupled to the circuit 9.

Thus in this figure if we assume that the receiver be tuned to resonance with a received carrier wave the amplification of tube 1 will be varied by action of the automatic volume control detector 11', 12' by an amount sufficient to maintain a substantially constant intermediate frequency electromotive force in the circuit 9 with the result that the amplification of discharge device 2 and the output signal remain substantially constant. The signal electromotive force in the circuit 9, however, varies to a certain extent. Owing to the fact that the voltage upon the circuit 38 is considerably smaller than 55 that upon the circuit 9 and also owing to the fact that the voltage produced on resistance 34 is opposed to that produced on resistance 21 in the direct current circuit between the cathode and grid of tube 2, the output from tube 2 is less 60 subject to variation than that from tube 1 and may be relatively constant. Thus the output volume of the radio receiver, when it is adjusted for resonance with the received carrier wave, is 65 maintained constant irrespective of fading.

During variation of the tuning of the receiver from resonance with the carrier wave the automatic volume control circuit tends to maintain a constant signal electromotive force in the circuit 9, but, owing to the greater selectivity of that portion of the receiver prior to the aural tuning rectifier 37 over that prior to the automatic volume control rectifier 11', 12', the carrier wave voltage in circuit 38 immediately reduces thereby 10 reducing the voltage on resistance 34 and causing the negative voltage produced by rectifier 11', 12' to become effective on the control grid of amplifier 2. This, of course, decreases the 15 amplification of the amplifier 2 and thus immediately reduces the output volume. Thus as the tuning control is operated through resonance to a carrier wave a distinct maximum of output volume occurs at the position of the tuning control where the receiver is in resonance with the 20 carrier wave whereby tuning of the receiver in accordance with the aural response is facilitated.

Fig. 4 differs from Fig. 3 only in that discharge device 2 in this case operates as a radio amplifier, the condenser 39 being connected between the grid of discharge device 2 and a point on the 25 tuned circuit 38. The element 35 in this case may comprise either a resistance or a choke coil, as desired. It is believed that the operation of this form of my invention will be apparent from the explanation already given.

The equipment illustrated in Fig. 5 differs from the forms of the invention already described in that the aural tuning voltage is applied, not to an amplifier subsequent in the circuit to the aural tuning rectifier, but to one prior thereto. In this case the automatic volume control voltage which appears on resistance 21 is supplied to the grid of discharge device 1 through filter resistance 23, resistances 34 and 35, and tuned 35 input circuit 8 of the amplifier 1. The aural tuning rectifier 37 produces a unidirectional voltage upon resistance 34 which is opposed to that on resistance 21 in the above-described circuit. However, the automatic volume control voltage 40 is sufficient to maintain constant volume when the radio receiver is in a fixed tuned condition. When the tuning of the receiver is varied, however, owing to the difference in selectivity of the receiver prior to volume control rectifier 11', 12' 45 and that prior to aural tuning rectifier 37, the reduction in voltage across circuit 38 due to variation in the intermediate frequency is sufficient to cause a rapid drop in voltage on resistance 34 thereby causing the grid of amplifier 1 to become 50 increasingly negative and the amplification of this device to be reduced. This in turn causes the output volume to vary in such a way as greatly to facilitate the tuning of the receiver by aid of the aural response. As thus arranged the 55 degree of aural tuning, however, and noise suppression arising out of aural tuning is limited by the fact that the minimum gain of the amplifier 1 must be sufficient to produce an appreciable output voltage across the load 34 of the 60 aural tuning control rectifier 37.

In Fig. 6 I have shown a further modification of my invention in which the low frequency amplifier 3 is one having an amplifier section similar to that shown in Fig. 1, the operation of 65 which is controlled by a diode 39. The diode 11', 12' operates for automatic volume control purposes in the same way as described in connection with Figs. 1, 3, 4, and 5, and similarly the diode 37 operates for aural tuning control similar to 70 the operation of the corresponding diode in Figs.

3, 4, and 5. The diode 39 in cooperation with the discharge device 3 operates to effect noise suppression.

It will be observed that the cathode of the discharge device 3 is connected to the negative side 5 of the supply source not only through the bias resistor 28 but also through a dropping resistance 40. The negative end of the dropping resistance is connected to the grid G₃ through a resistance 41, connected across the diode 39, and 10 a filter comprising resistance 42 and condenser 43. The cathode of the diode 39 is connected through coupling condenser 44 to one side of the aural tuning circuit 38 whereby this discharge device is effectively energized with high frequency oscillations. The grid G₃, in the absence 15 of a signal of greater than a predetermined intensity, is sufficiently negative with respect to the cathode to prevent the flow of anode current and thus audio output is precluded from this device. Resistance 41 is so poled, however, that when signals of greater than a predetermined intensity are received the negative voltage of the grid G₃ is reduced to such an extent that current 20 starts to flow in the anode of the discharge device. The voltage appearing on resistance 41, however, is sufficiently great to cause the tube 3 to produce a switch-like action whereby the output signal when sufficiently reduced from normal suddenly drops to zero. In this way noise 25 suppression during periods when the receiver is off tune with any carrier wave or when the received signals are of less than a predetermined intensity is effective.

In other respects the operation of the equipment of Fig. 6 will be readily understood from the explanation already given it being noted further only that the additional tuned circuits 45 and 46 are interposed between circuit 9 and circuit 38 to increase the difference in selectivity 40 between the portion of the receiver prior to the automatic volume control diode 11', 12' and that portion prior to the aural tuning control diode 37. These circuits are connected together across the power supply mains by capacity 47 and may, of 45 course, be employed in connection with the equipment of any of the figures if increased selectivity between circuits 9 and 38 be desired.

In all of the figures previously described the selectivity of the system prior to demodulation of the carrier wave for reproduction of the desired signal is the same as that for aural tuning control.

In Fig. 7 I have shown the aural tuning control rectifier 37 coupled to the tuned circuit 9 through the additional tuned circuit 48, electron discharge amplifier 49, and tuned circuits 50. A diode 51 in series with load resistance 52 is connected across the circuit 48, this diode having its load resistance connected through the audio coupling condenser 53 to the grid of audio amplifier 2. Thus the selectivity of that portion of the receiver prior to aural tuning control diode 37 is much greater than that of that portion of the receiver prior to the demodulator 51. In this way the peak of output signal intensity as the receiver is tuned through resonance is more marked.

The circuit arrangements illustrated in Figs. 1 and 6 and employing discharge devices of the type indicated at 3 in both of said figures are described and claimed in my copending application Serial No. 99,245 filed September 3, 1936 and assigned to the same assignee as my present application.

While I have shown particular embodiments of my invention it will of course be understood that I do not wish to be limited thereto since many modifications both in the circuit arrangement and in the instrumentalities employed may be made, and that I contemplate by the appended claims to cover any such modifications as fall within the true spirit and scope of my invention.

What I claim as new and desire to secure by

5 Letters Patent of the United States, is,—

10 1. In combination, a high frequency amplifier having an amplification control electrode, a circuit connected to the output of said amplifier, means to supply two opposed unidirectional electromotive forces to said control electrode, one of said electromotive forces varying directly with the intensity of the signal currents in said output and poled to reduce the gain of said amplifier, and the other of said electromotive forces varying directly as the intensity of signals at a certain point in said circuit, and frequency selective means between said output of said amplifier and said certain point.

15 2. In combination, an amplifier having a gain control electrode, means to supply two opposed unidirectional electromotive forces to said electrode, one of said electromotive forces varying directly as the intensity of signals supplied to said amplifier and poled to reduce the gain of said amplifier, frequency selective means, means to supply oscillations having the frequency of oscillations amplified by said amplifier to said frequency selective means, and means to rectify said oscillations after traversing said frequency selective means to produce the other of said two opposed unidirectional electromotive forces.

20 3. The combination, in a high frequency receiver, of an amplifier having a control electrode

25 circuit having opposed unidirectional electromotive forces therein, means to produce one of said electromotive forces by rectification of the received carrier waves at one point in said receiver, means to produce the other of said electromotive forces by rectification of the received carrier wave at a different point in said receiver, and a frequency selective circuit connected between said points.

30 4. The combination, in a high frequency receiver, of a pair of electron discharge amplifiers, a frequency sensitive circuit between said amplifiers, means to transmit received oscillations through said amplifiers and circuit, means to produce two unidirectional electromotive forces, one of said electromotive forces varying directly as the intensity of said oscillations on one side of said circuit and the other of said electromotive forces varying directly as the intensity of oscillations on the other side of said circuit, means to control the amplification of one of said amplifiers in accordance with the magnitude of one of said electromotive forces, and means to control the amplification of the other of said amplifiers in accordance with the difference in said electromotive forces.

35 5. The combination, in a radio receiver, of an amplifier including an electron discharge device, means to control the amplification of said electron discharge device in opposite senses in response to the intensity of high frequency oscillations at different respective points in said receiver, said means being operative to effect said control during desired reproduction of signals by said receiver, and means to transmit said oscillations from one of said points to the other through a frequency selective circuit.

ERNEST YEOMAN ROBINSON.
